SIMULATED BOWLING GAME DEVICE

Robert Harvey Galbreath, Denver, Colo.

Application September 14, 1953, Serial No. 379,841

7 Claims. (Cl. 273—127)

10

This invention relates to a bowling game, and has for its principal object the provision of a single, unitary game device which can be used upon a floor or lawn for simulating a conventional bowling alley.

Another object of the invention is to provide a bowling game in which a player rolls two bowling balls by hand, similar to the usual game of bowling or ten pins, and to provide a game device which will act to extinguish lights to represent the pins which are knocked down by the balls.

A further object is to provide a bowling game device of this character in which lighted targets represent the pins remaining standing after a ball is bowled, to indicate to the bowler the proper position to direct his second ball.

A still further object is to provide a bowling device with an indicating target which when struck by a ball will act to multiply the score obtained by the other ball.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a front view of the improved lawn bowling game;

Fig. 2 is an enlarged end view thereof;

Fig. 3 is a still further enlarged cross-section, taken on the line 3—3, Fig. 1;

Fig. 4 is a rear view thereof on the same scale as Fig. 1, partially broken away to show interior construction;

Fig. 5 is a wiring diagram illustrating the arrangement of the electric circuits employed in the improved game device; and

Fig. 6 is a simplified circuit diagram, illustrating the basic electric circuits employed in the game device.

In Fig. 5 the circles indicate electric lamps. For the purpose of simplification, the circuit from a supply main to one side only of each lamp is illustrated in the diagram. It is to be understood that the other side of each lamp is connected to a second supply main common to all lamps.

While the game is particularly intended as a lawn bowling game, it is, of course, not limited to this particular location, as it can be played on any suitable level surface adaptable to the rolling of balls. It will be herein referred to, however, as a lawn bowling game.

The improved game device employs balls 23 of any desired size. Balls similar to the larger croquet balls have been found to be satisfactory.

The balls are rolled toward an elongated housing 11

5

upon which a score-indicating board 12 is supported in any desired manner, such as by means of ornamental supporting brackets 13. The elongated housing is provided with a relatively thin floor 14 having an inclined, beveled forward edge 15 which directs the balls onto the floor 14.

The housing is provided with a backing 16 provided with a plurality of spaced-apart window openings 17 along its lower portion. A stop strip 18 extends along the backing 16 and is preferably provided with a cushion strip 19 of sponge rubber or similar material for absorbing the impact of the balls 23.

A vertically-moving hinged flap 20 is positioned over each of the window openings 17 throughout the length of the housing 11. The forward extremities of the flaps 20 are hinged to and below a casing strip 21 upon any suitable hinges 22. The rear extremities of the flaps 20 rest upon the stop strip 18.

The casing strip 21 is rabbeted to receive a plurality of aligned micro-switches, there being one of the switches above the medial portion of each of the flaps 20, as indicated at S10 in Fig. 3. These switches are of any standard variety having a spring-projected operating knob 24 which, when forced into the switch acts to break or make an electrical circuit. The switches are secured to the casing strip in any desired manner, such as by means of suitable screws 25.

The upswing of the flaps 20 is limited by means of a limit strip 26 secured to the backing 16. A wiring channel 27 is provided along the backing 26 for receiving the electrical circuit wires of the device. Wiring openings 48 communicate with the wiring channel 27.

The flaps 20 are constantly urged downwardly against the stop strip 18 by gravity and by the spring-actuated knobs 24 of the micro-switches. Should additional urging be desired, springs 47 may be provided to react against and urge the flaps downwardly. The flaps 20 are positioned relative to the floor 14 so that when a ball 23 passes beneath a flap 20, it will swing the latter upwardly sufficiently far to contact the operating knob 24 of the adjacent micro-switch to operate the latter. It is preferred to position the limit strip 26 so that it will act to stop the upward movement of the extremity of the flap 20 slightly before the balls 23 strike the stop strip 18 so as to create a wedging action between the floor and the flap to retard the flight of the ball.

It is desired to call attention to the fact that the sharpened forward edge 15 of the floor 14 terminates rearwardly of the forward face of the casing strip 21 so that the ball will have entered beneath its flap 20 before it is forced upwardly onto the floor 14.

A light chamber 28 is positioned to the rear of each of the window openings 17. The light chambers 28 are separated from each other by means of light impervious partitions 38 and each light chamber contains an electric target lamp carried in a suitable lamp socket 29. The lamps are positioned above the windows 17 to be somewhat distant from the impact point of the ball to prevent breakage of the electric lamps.

The bottom of each light chamber 28 may be provided with an inclined reflecting surface 30, preferably covered with light-reflecting bead paint to reflect the light from the lamps forwardly through the window openings 17.

Access is had to the light chambers 28 through the medium of rear doors 31 depending from hinges 32 and secured by means of suitable latches 33.

In the preferred game device, there are eleven of the window openings 17 and eleven of the flaps 20. The flaps are placed in close proximity to each other so as to provide a substantially continuous inclined ceiling over the ball-receiving portion of the housing 11.

2

The score-indicating board 12 is mounted in a suitable enclosing frame 34 having a removable back 35. The board 12 is provided with ten openings in triangular arrangement, similar to the arrangement of the setting of bowling pins. Each of these openings is provided with a lamp-receiving socket 36, preferably of the type known as "sign sockets" which can be attached through openings in a supporting member. An electric signal lamp is positioned in each socket 36.

In addition to the ten triangularly-arranged sockets, two additional sockets are provided, one for supporting a colored "strike" or "spare" indicating lamp, indicated by the letter S and a "double" indicating lamp, indicated by the letter D. An electrical receptacle 37 is provided at one extremity of the housing 11 to receive an electrical conductor cord for conveying current to the game apparatus.

The game is wired according to the schematic circuit diagram of Fig. 6, wherein the lamps in the light chambers 28 are designated by the numerals 1 to 10, inclusive. The number used to designate each lamp will indicate the number of lamps extinguished at the time any given lamp is extinguished, as will be later described.

The lamps in the score-indicating board 12 are indicated on the diagram by the prime numbers from 1 to 10, each prime-numbered lamp corresponding to one of the non-prime-numbered lamps. In other words, the number 6' lamp will illuminate and extinguish simultaneously with the number 6 lamp. The lamp in the furthermost light chamber to the right will be indicated by the letter D which functions in cooperation with the lamp D' on the score board 12.

The micro-switch associated with each pair of lamps will be herein designated by a number corresponding to the number of the lamps it controls and preceded by the letter S, thus, micro-switch S2 will control lamps 2 and 2'. The micro-switch controlling lamp D will be herein designated as SD.

Each pair of lamps from 1 to 10 is connected through the medium of connecting wires 39 to a first current supply main 40. The lamps S, D, and D' are connected by means of a connecting wire 46 to the current supply main 40. Micro-switch S10 is connected to a second current supply main 41. The current flows from micro-switch S10 to micro-switch S9, thence to micro-switch S8, and continues through each successive micro-switch by means of interconnecting switch wires 42 and micro-switch S1 is reached.

Thus all of the micro-switches from S1 to S10 are in series with each other. The micro-switches S1 thru S10 are of the normally closed type which open a circuit when pressure is applied to the knob 24. The far side of each micro-switch S1 thru S10 is connected in multiple by means of a lamp wire 43 to the two lamps designated by the same number as the respective micro-switch.

Micro-switch S10 is of the double-throw variety, that is, it is provided with "make" contacts as well as "break" contacts. The "make" contact of micro-switch S10 is connected to the colored "strike" lamp S. The micro-switch SD is of the normally open variety, as opposed to the other switches, and acts to close a circuit through a lamp wire 44 communicating with the "double" lamp D'.

Let us assume that a player rolls a ball 23 toward the housing 11, and that this ball strikes the flap 20 below micro-switch S9, as indicated in Fig. 1. This causes the flap 20 to swing upwardly to actuate its micro-switch S9 so as to break the circuit immediately ahead of lamps 9 and 9'. This stops the flow of current to all of the lamps except 10 and 10', as can be seen from a study of Fig. 6. The only light remaining on the score board 12 is 10'. Nine lamps have been extinguished on the score board 12 and the only window openings 17 remaining illuminated are those below lamp 10 and below lamp D. The score is nine.

The player can now choose whether to roll toward the window illuminated by lamp 10 or toward the window illuminated by lamp D. Should he roll to the former window opening, the ball will extinguish lamps 10 and 10', giving a score of ten. Should he roll to the window below lamp D, the ball will cause the flap 20 thereover to close micro-switch SD and illuminate lamp D', which will indicate he may double his original score of nine to produce a score of eighteen.

10 Should his roll toward the window below lamp 10 be successful, it will cause the double-throw micro-switch S10 to close a circuit through wire 45 to the "spare" and "strike" indicating lamp S to indicate he has obtained either a "spare" or a "strike," depending upon whether 15 it was the first or second ball. The "spare" or "strike" will be scored similarly to the usual bowling scoring rules.

It is preferred to use colored lamp bulbs for the lamps S, D, and D', and to use white lamps for the remaining 20 lamps. If the lamps S and D' are colored, they will not visibly interfere with the white triangle formed on the score board by the ten white lamps. If the lamp D is colored, it will not visibly interfere with the ten white-lighted window openings simulating the ten bowling pins.

25 It is preferred to form the flaps from a relatively stiff yet flexible material, such as tempered "Masonite," so that they may flex to retard the impact of the balls.

In the following claims, the non-prime-numbered lamps 30 in the light chambers 28 will be referred to as "target" lamps, and the prime-numbered lamps will be referred to as "signal" lamps. The imaginary cubicle before each window opening 17 and below each flap 20 will be referred to in the claims as a "ball-receiving chamber," and the window openings 17 will be referred to as 35 "targets."

While a specific form of the improvement has been described and illustrated herein, it is desired to be understood that the same may be varied, within the scope of the appended claims, without departing from the spirit 40 of the invention.

Having thus described the invention, what is claimed and desired secured by Letters Patent is:

1. A simulated bowling game comprising: an elongated housing adapted to be positioned transversally of the path of a rolling ball; a plurality of aligned illuminated target windows in said housing; an elongated open-fronted, ball-receiving chamber positioned forwardly of said windows; a floor in said chamber; a plurality of hinged flaps forming the ceiling over said ball-receiving chamber, there being one of said flaps positioned forwardly of and above each window, said flaps being positioned relative to said floor so that when said ball rolls onto said floor, it will wedge between the floor and one of said flaps so as to force the flap upwardly; signal lamps; and an electric switch positioned to be actuated in consequence of the upward movement of each of said flaps, each of said switches being in circuit with one of said signal lamps so as to give an indication when the flap associated therewith is swung upwardly.

60 2. A simulated bowling game as described in claim 1 having a target lamp illuminating each of said windows, each of said target lamps being in circuit with the switch associated with the flap positioned forwardly of its respective window, said switches being normally closed so that when a flap is moved upwardly under the wedging action of said ball, its associated switch will be opened to simultaneously extinguish both the target lamp and the signal lamp in circuit with the latter switch.

3. A simulated bowling game as described in claim 2 in which all of the switches are connected in series so that the opening of any given switch will de-energize the succeeding switches in said series and their associated signal and target lamps.

4. A simulated bowling game comprising: an elongated 75 housing adapted to be positioned transversally of the path

of a rolling ball; an elongated open-fronted, ball-receiving chamber in the front of said housing; a plurality of longitudinally aligned lamp chambers in the rear of said housing; a window communicating between each lamp chamber and said ball-receiving chamber; a target lamp in each lamp chamber illuminating the window therein; a plurality of inclined flaps; hinge means hingedly mounting the forward extremities of said flaps to said housing above the open front thereof, there being one of said flaps positioned above and forwardly of each window to form a substantially continuous ceiling over said chamber; a floor in said ball-receiving chamber, the vertical distance between each flap and said floor being normally less than the diameter of said ball so that when a ball enters on said floor, it will urge the flap thereover upwardly; and a normally closed electric switch positioned to be actuated by each flap, each of said switches being in circuit with one of said target lamps so that when one of said flaps is urged upwardly by said ball, its associated window will be darkened.

5. A simulated bowling game as described in claim 4 having a score board positioned above said housing; and a plurality of signal lamps supported on said score board, said lamps being arranged in triangular arrangement similar to the conventional setting of bowling pins, said signal lamps being also in circuit with said switches so that the extinguishment of a given target lamp will simultaneously extinguish one of said signal lamps in said triangular arrangement.

6. A simulated bowling game comprising: a housing having an open front adapted to receive a rolled ball, said housing being elongated transversely of the path of said ball, said front opening extending the full width of said housing; a backing in said housing provided with a plurality of spaced window openings; a lamp chamber positioned rearwardly of each window opening; a target lamp in each chamber illuminating the window opening

thereof; a casing strip positioned along the top of said front opening; hinge means mounted on said casing strip; a plurality of flaps hingedly supported by said hinge means and extending rearwardly and downwardly toward said backing, there being one of said flaps positioned forwardly of each window opening, said flaps being positioned in relatively close alignment to form a substantially continuous ceiling in said housing; limit means positioned in the path of the rear extremities of said flaps and acting to limit the vertical movement of said extremities; spring means urging said extremities downwardly; an electric circuit-opening device positioned to be contacted and actuated by the upward movement of each flap, each of said circuit-opening devices being in circuit with one of said lamps so that upward movement of any flap will darken the window opening positioned rearwardly thereof; and a floor fixedly mounted in said housing and positioned to receive a ball and retain the latter in wedged relation to one of said flaps.

20 7. A simulated bowling game as described in claim 6 in which the forward edge of said floor is positioned rearwardly of the forward hinged extremities of said flaps.
